CLAIM

The ornamental design for a fastener cap, as shown and described.

DESCRIPTION

FIG. 1 is a top, front, right perspective view of the fastener cap in accordance with my new design;
FIG. 2 is a bottom, rear, left perspective view thereof;
FIG. 3 is a bottom, front, left perspective view thereof;
FIG. 4 is a top, rear, right perspective view thereof;
FIG. 5 is a front view thereof;
FIG. 6 is a rear view thereof;
FIG. 7 is a left side view thereof;
FIG. 8 is a right side view thereof;
FIG. 9 is a top view thereof;
FIG. 10 is a bottom view thereof;
FIG. 11 is a top, front, right perspective view of the fastener cap showing the appearance when the subject design is attached in a strip;
FIG. 12 is a bottom, rear, left perspective view thereof;
FIG. 13 is a bottom, front, left perspective view thereof; and,
FIG. 14 is a top, rear, right perspective view thereof.
In the drawings, the broken lines show portions of a fastener cap that forms no part of the claim.
